UNITED STATES PATENT OFFICE.

EDWIN D. BAXTER, OF MANSFIELD, OHIO, ASSIGNOR TO THE BAXTER STOVE COMPANY,
OF MANSFIELD, OHIO, A CORPORATION OF OHIO.

STOVE.

1,195,329.

Specification of Letters Patent. Patented Aug. 22, 1916.

Application filed February 6, 1915. Serial No. 6,431.

To all whom it may concern:

Be it known that I, EDWIN D. BAXTER, a citizen of the United States of America, residing at Mansfield, in the county of Rich-
5 land and State of Ohio, have invented cer-
tain new and useful Improvements in
Stoves, of which the following is a specific-
cation.

This invention relates to certain new and
10 useful improvements in stoves and the primary
object thereof is to provide a unitary
stove structure which can be used to burn
solid and gaseous fuel either simultaneously
or separately and to enable the stove to be
15 easily, quickly and conveniently changed or
converted for burning solid and gaseous
fuel, separately or simultaneously, which
change can be effected without the removal
of bolts, screws or the like.

20 A further object of the invention is to
provide means whereby the products of
combustion may be conducted either sepa-
rately or simultaneously from the solid and
gaseous fuel to the stove top and to also
25 enable the oven and stove top to be heated
by use of either fuel.

A still further object of the invention is
to provide a stove which can be rapidly con-
verted to consume fuel of the variety which
30 is most accessible or economical to the user
for either heating or cooking purposes.

Other and further objects are to gener-
ally improve, simplify and economize in
the structure of stoves of the character to which
35 the invention relates and to enable the in-
vention to be carried into practice by use of
minimum parts which are compact and are
highly efficient in use.

In the drawings: Figure 1 is a top plan
40 view of the invention as used for burning
both fuels; Fig. 2 is a front side elevation;
Fig. 3 is a rear side elevation partly in sec-
tion; Fig. 4 is a sectional view on the line
45 4-4 of Fig. 3; Fig. 5 is a central longitudi-
nal sectional view of Fig. 1; Fig. 6 is a
section taken on the line 6-6 of Fig. 5;
Fig. 7 is a fragmentary longitudinal sec-
tional view of Fig. 1 showing the stove ar-
50 ranged to burn solid fuel; and Fig. 8 is a
sectional view on the line 8-8 of Fig. 7.

In proceeding in accordance with the
present invention, the stove 1 which may be
of cast iron, or sheet metal, is provided

with the usual heat chamber or passage 2
formed by and between the oven top 3 and 55
the stove top 4.

A series of gas burners 5 for heating the
stove top are disposed in the passage 2 and
are removably secured in position by any
appropriate means. 60

The main flue or pipe 6 is provided with
offset or lateral chambers 7 and 8 which
communicate therewith through openings 9'
and 10' respectively, formed in the sides of
the flue 6, the end of the stove having open- 65
ings 9 and 10 which establish communica-
tion between the respective chambers 7 and
8 and the passage 2. Sliding dampers 11
and 12 control the openings 9 and 10 re-
spectively, while a hinged damper 13 oper- 70
able by a handle 14 projecting above the
stove top, controls an opening 13' which
establishes communication between the flue
6 and the passage 2.

The fire box 15 is provided with a con- 75
ventional form of duplex grate 16 to enable
solid fuel of different character to be burned.

Referring now to Figs. 5-8 of the draw-
ings, it will be apparent that the bottom
of the oven is provided with a lateral cut- 80
out portion bounded on its sides by ledges
17 and 18, which latter removably support
a box-like carrier *a* by engaging side flanges
19 and 20 formed on said carrier. A gase-
ous fuel burner 21 is appropriately con- 85
nected to the carrier *a*.

As just stated the carrier *a* is removable,
and when removed, the opening wherein
same is received is closed by a plate 22
having shouldered flanges 23 and 24 which 90
interfit with the ledges 17 and 18 as de-
picted in Fig. 7 of the drawings. The plate
22 is utilized when it is desired to heat the
oven solely with solid fuel.

Preferably the plate 22 carries an in- 95
clined deflector strip 25 which depends
therefrom and traverses the heat passage
below the oven so as to assure uniform dis-
tribution of the heat below the oven. A
pipe 26 supplies gaseous fuel to the series 100
of top burners 5 and the bottom burner 21.

For the purpose of preventing the prod-
ucts of combustion from and when solid fuel
is used entering the passage 2, a partition
or baffle plate 29 is employed which, as 105
shown in Fig. 1 extends across passage 2 and

is removably fastened to the oven top 3 by means of lugs 29^a borne by the partition 29 and engaged by swinging or pivoted cam latches 30 that are connected to the oven top 3. A series of apertures 31 formed in the flue 6 are controlled by a sliding plate 33 as depicted in Figs. 5 and 8, and are employed for the purpose of allowing escape of the products of combustion into the flue 6, when the burner 21 is used.

As shown in Fig. 2 of the drawings, a sliding strip 34 has slots through which screws 35 pass, the screws being secured to the stove body, the strip being employed to 15 control the openings through which the supply pipes to burners 5 pass and thus govern the amount of air which enters passage 2 and is fed to the burners 5.

The lower portion of the flue 6 is provided with an inlet 39 as shown in Fig. 7 which communicates with the bottom and rear heat passages 38 and 37 respectively.

In operation, when it is desired to heat the oven with gaseous fuel, the burner carrier *a* is placed in position, and the slide 33 is moved to uncover the apertures 31.

When solid fuel is to be burned, carrier *a* is removed and plate 22 is placed in position in the oven bottom, the partition 29 being 30 retained in place, thus permitting the products of combustion to enter flue 6 through openings 9 and 9' or if desired the products of combustion may be permitted to directly enter the flue through opening 13' by opening 35 the damper 13 and removing the partition 29.

In event of the oven being heated by use of solid fuel, the dampers 11, 12 and 13 are closed, thereby causing the heat to pass over 40 the oven top *i. e.* through passage 2, then down flue 37, through flue 38 and entering opening 39, passes up flue 6.

When the oven is heated by use of gaseous fuel, air is admitted to burner 21 45 through an opening 40, Fig. 2, which opening may be closed by a plate, not shown, when the oven is heated by the use of solid fuel.

The above described structure provides a 50 stove that can be readily used in event of gaseous fuel being unavailable or upon reduction of gas pressure, and also enables the stove to be used to burn solid fuel, debris, garbage or other refuse, and at the same time 55 gas, if desired.

What is claimed is:

1. In a stove having an oven the bottom of which is provided with a cut out portion, a heat passage below the oven, and a flue having an opening leading into said passage, a burner carrier removably engaged in said cut-out portion, and an imperforate plate for closing said cut out portion when the carrier is removed, said plate having a depending heat deflecting strip which extends 65 across the heat passage beneath the oven and is disposed to the rear of the flue opening and is adapted to have an end thereof engage a side wall of the heat passage.

2. In a stove having an oven and a heat 70 passage thereabove, a heat deflector having its lower longitudinal free edge seated upon the top of the oven and having outwardly extending lugs which also seat upon the oven top, a series of pivoted cam latches pivoted 75 to the oven top and engageable with said lugs to removably sustain the deflector in position.

3. In a stove having an oven with heat 80 passages above and below same, a flue having a lower opening leading into the lower passage, said flue having an upper opening leading into the upper passage, means to control said upper flue opening, a pair of lateral chambers on opposite sides of the flue communicating therewith and with the upper passage, and means to independently control the communications of said lateral chambers with the upper passage:

4. In a stove having an oven with heat 90 passages above and below same, a flue having a lower opening leading into the lower passage, said flue having an upper opening leading into the upper passage, means to control said upper flue opening, a pair of 95 lateral chambers on opposite sides of the flue communicating therewith and with the upper passage, means to independently control the communications of said lateral chambers with the upper passage, and a removable deflector in the upper heat passage 100 adapted to extend entirely thereacross and to enable the heat to enter one of said chambers and therethrough enter the flue.

In testimony whereof I affix my signature 105 in presence of two witnesses.

EDWIN D. BAXTER.
